UNITED STATES PATENT OFFICE.

OLIVER FRED SELLE, OF ST. LOUIS, MISSOURI.

DESIGN FOR A FLAG, PENNANT, SIGN, EMBLEM, OR ARTICLE OF A SIMILAR NATURE.

53,138.

Specification for Design.

Patented Mar. 25, 1919.

Application filed December 31, 1918. Serial No. 269,162. Term of patent 7 years.

To all whom it may concern:

Be it known that I, OLIVER F. SELLE, a citizen of the United States, and a resident of St. Louis, State of Missouri, United States of America, have invented a new, original, and ornamental Design for a Flag, Pennant, Sign, Emblem, or Article of a Similar Nature.

Reference is to be had to the accompanying drawing, in which the figure is an elevation of an emblem showing my new design.

I claim:

The ornamental design for a flag, pennant, sign, emblem, or article of a similar nature, as shown.

OLIVER FRED SELLE.
